ATTORNEY

UNITED STATES PATENT OFFICE.

LOUIS B. PRAHAR, OF NEW YORK, N. Y.

DESIGN FOR A BUCKLE.

SPECIFICATION forming part of Design No. 33,454, dated October 30, 1900.

Application filed October 6, 1900. Serial No. 32,310. Term of patent 31 years.

To all whom it may concern:

Be it known that I, LOUIS B. PRAHAR, a citizen of the United States, residing in the city of New York, borough of Brooklyn, in the county of Kings and State of New York, have invented and produced a new and original Design for Buckles, of which the following is a specification, reference being had to the accompanying drawing, forming a part thereof.

The drawing represents a face view of the buckle embodying the new design.

As shown in the drawing, the leading or material feature of the design consists of the two end portions A A', which simulate lyre-shaped wreaths of flowers, the connecting bar portion B, and the curved center portion C, or-

namented with scrollwork. The lyre-shaped portions A A' have their convex bases presented outwardly, and their inwardly-presented branches extend substantially up to the curved center portion C. The bar portion B has a scroll-like ornamentation *b* at its middle part.

What I claim is—

The design for a buckle as shown and described.

In witness whereof I have hereunto signed my name, this 4th day of October, 1900, in the presence of two subscribing witnesses.

LOUIS B. PRAHAR.

Witnesses:

PETER A. ROSS,
F. W. WIMAN.
